CHUTE ASSEMBLY

George F. Yager, Toledo, Ohio, assignor to The Bunting Brass & Bronze Company, Toledo, Ohio, a corporation of Ohio

Original application December 15, 1930, Serial No. 502,526. Divided and this application July 3, 1933, Serial No. 678,977

18 Claims. (Cl. 90—33)

This invention relates generally to chute assemblies and constitutes a division of my application Serial No. 502,526 filed December 15, 1930.

In the accompanying drawings:

Figure 1 is a fragmentary top plan view of the chute assembly;

Figure 2 is an elevation of the structure illustrated in Figure 1;

Figure 3 is a sectional side elevation of the chute assembly and associated machine parts;

Figure 4 is a sectional view taken on the line 4—4 of Figure 2.

Referring now to the drawings, A is the supporting bracket; B and C respectively are the work chutes and D is the work receiver or support of an assembly embodying my invention. As shown, the bracket A has substantially parallel upright sides 1 and 2 respectively and is provided at opposite ends thereof with inverted substantially L-shaped recesses 3 and 4 respectively for receiving the rails 5 and 6 of a frame E corresponding to 16 in my application, Serial No. 502,526. Preferably the bracket A is provided at spaced points longitudinally of its lower edge with downwardly opening substantially semi-circular openings 7 and 8 respectively and is provided at opposite ends thereof above the recesses 3 and 4 with laterally projecting attaching portions 9 and 10 respectively. As shown, the top part 11 of the attaching portion 9 inclines downwardly and inwardly from the left end of the bracket upon the side 2 thereof to a point substantially in vertical alignment with the upright wall 12 of the recesses 3, while the top part 13 of the attaching portion 10 is substantially horizontal and is disposed upon the side 2 at substantially right angles to the upright wall 14 of the recess 4. Any suitable means such as the bolts 15 may be used to secure the attaching portions 9 and 10 to the rails 5 and 6 of the frame.

The work chute B preferably comprises two sections or runways F and G respectively arranged at substantially an obtuse angle to each other with the joint therebetween at approximately the inner lower end of the inclined part 11 of the attaching portion 9, while the chute C preferably comprises two sections or runways H and I respectively arranged at substantially right angles to each other with the joint therebetween at approximately the inner end of the horizontal part 13 of the attaching portion 10. The runway F is secured upon the inclined part 11 and is located upon the side 2 of the bracket. As shown, a portion 18 of the runway F extends to an upright edge 19 of the bracket and is sub-

stantially channel shaped, while the lower part 20 of the runway upon the side 2 is substantially L-shape in cross section and cooperates with the said side 2 to form a channel for the work. The runway G is substantially L-shape in cross section and also cooperates with the side 2 of the bracket to form a channel for the work. Preferably this runway G is hingedly connected at its upper end and is adjustably connected at its lower end to the bracket A so that it may be moved in an arc about the pivot 21 to direct work of various sizes to a point in line with the opening 7 in the lower edge of the bracket. A shield 22 is adjustably connected to the bracket A in substantially parallel relation to the runway G and is provided at its upper end with an angularly projecting extension 23 that overlaps the lower end of the runway F. Thus the work will be guided from the runway F into the runway G and will be held in the latter for proper delivery to the receiver D in line with the opening 7. The runway H is located above the chute B and is secured to laterally projecting portions 24 and 25 respectively of the bracket A. Preferably this runway H is channel shape and curves downwardly over the upper edge of the bracket A to the side 2 at a point adjacent an upright edge 26 of the bracket. The runway I is substantially L-shape in cross section and cooperates with the side 2 of the bracket to form a channel. As shown, this runway I is pivoted at its upper end and is adjustably connected adjacent its lower end to the bracket A whereby it may be moved in an arc about the pivot 27 to direct work of various sizes to a point in line with the opening 8 in the bracket. An angularly disposed shield 28 bolted to the attaching portion 10 serves to guide the work from the runway H to the runway I, while a shield 29 adjustably mounted on the side 2 of the bracket in substantially parallel relation to the runway I serves to retain the work in the runway I while moving longitudinally thereof to the point in line with the opening 8.

The receiver or support D is also carried by the bracket A and is preferably adjustably secured thereto substantially midway between the openings 7 and 8 whereby it may be raised and lowered relative to the bracket. Preferably this receiver D is provided in substantially vertical alignment with the openings 7 and 8 with upwardly opening channels or grooves 30 and 31 respectively for receiving the work discharged from the runways G and I respectively. As shown, these grooves 30 and 31 in effect constitute the lower sides of the openings 7 and 8,

hence the said openings may be made larger or smaller if desired by the adjustment of the receiver D vertically relative to the bracket A to accommodate work of various sizes.

- 5 In use the work such as bushings to be broached may be fed by any suitable means (not shown) into the runways F and H of the chutes B and C so that such work will roll down the said runways to the runways G and I and thence to the
- 10 grooves 30 and 31 respectively in the receiver D. The runways G and I, shields 22 and 29, and receiver D may be readily adjusted if desired to accommodate work of different sizes and any suitable means (not shown) may be used to remove the work from the grooves 30 and 31 in the receiver into suitable jaws (not shown) so that said work may be subsequently engaged by broaches or other suitable tools. One example of the means, jaws, etc., just mentioned is illustrated in my application, Serial No. 502,526.
- 15 20 While it is believed that from the foregoing description the nature and advantages of the invention will be readily apparent, I desire to have it understood that I do not limit myself to what is herein shown and described and that such changes may be resorted to when desired as fall within the scope of what is claimed.

What I claim as my invention is:

1. In a machine of the class described, a bracket having a substantially flat upright side and having an opening extending transversely thereof, and means for delivering work to a point in substantially horizontal alignment with the opening including a chute having two runways arranged substantially end to end, one of said runways being fixed to the bracket, and having a portion of substantially L cross section cooperating with the flat side aforesaid of the bracket to form a channel for the work, and the other of said runways being pivotally connected to the bracket and substantially L-shape in cross section whereby said runway and flat side aforesaid of the bracket form a channel for the work.
2. In a machine of the class described, a bracket attachable to a frame of a machine, a chute carried by the bracket including two runways, one being fixed to the bracket, and the other being adjustable relative to the fixed runway and disposed at an angle thereto, and means for directing work from the fixed runway into the movable runway including a shield carried by the bracket and having a part overlapping the fixed runway.
3. In a machine of the class described, a frame, a bracket member secured to the frame and having an upright face, a substantially horizontal work supporting member secured to the bracket, means for delivering work to the work supporting member including a chute having two runways arranged substantially end to end and carried by the bracket, each runway being L shape in cross section and cooperating with the upright face of the bracket to provide upper and lower channels for the work, and means for maintaining the work in the lower channel including a shield adjustably mounted on the upright face of the bracket member in substantially parallel relation to the base of the lower channel and having an extension overlapping the lower end of the upper channel.
4. In a machine of the class described, a bracket provided in its lower edge with a downwardly opening substantially semi-circular opening for the work, and a work receiver suspended from
- 75 said bracket and having a substantially horizon-

tal portion provided in substantially vertical alignment with the semi-circular opening with an upwardly opening channel for receiving and supporting the work in said opening, said work receiver being adjustable vertically relative to said bracket to vary the area of the space between the base of the channel and the upper edge of the opening to compensate for work of different sizes.

5. In a machine of the class described, a bracket provided in its lower edge with a downwardly opening substantially semi-circular opening for the work, a work receiver suspended from said bracket and having a substantially horizontal portion provided in substantially vertical alignment with the semi-circular opening with an upwardly opening channel for receiving and supporting the work in said opening, and means carried by said bracket for delivering work into the space between the base of the channel and the upper edge of the opening, said means including a runway pivotally mounted at its upper end on the bracket and adjustably connected at its lower end to the bracket so that it may be moved in an arc about its pivot to direct work of various size to the space between the base of the channel and the upper edge of the opening.

6. In a machine of the class described, the combination with a supporting frame having laterally spaced rails, of a vertically disposed plate-like bracket having inverted substantially L-shaped recesses at opposite ends thereof receiving said rails, said bracket being provided at spaced points longitudinally of its lower edge with downwardly opening substantially semi-circular openings for the reception of the work, said bracket being provided above said recesses with laterally projecting attaching portions engaging said rails, means engaging said attaching portions for securing the bracket to the rails, and means for directing work from points above the bracket toward the openings aforesaid in the lower edge thereof including means carried by said attaching portions.

7. In a machine of the class described, a bracket adapted to extend transversely of a machine frame and having attaching portions at opposite ends thereof for rigid attachment to a suitable support, said bracket being provided in its lower edge with a downwardly opening substantially semi-circular opening for the work, and means for delivering work to a point in substantially horizontal alignment with said opening including a chute having an inclined runway rigid with said bracket, and a cooperating runway pivotally mounted at its upper end on the bracket adjacent the lower end of the inclined runway and adjustably connected to the bracket at its lower end for movement relative to said opening.

8. In a machine of the class described, a bracket attachable to a frame of a machine and having an upright face, an inclined work chute upon said upright face, and a substantially horizontal member having an upwardly opening recess for receiving work from the chute and having an upright portion carried by said upright face, said member being adjustable relative to said bracket, and a portion of the chute being slidable on said upright face relative to the recess in said member whereby said chute and member may handle work of various sizes.

9. In a machine of the class described, a frame, a bracket member secured to the frame and hav-

ing an upright face, a substantially horizontal work supporting member secured to the bracket member and having an upwardly opening recess for receiving the work, and means for delivering work to the recess in said work supporting member including an angle bar upon and cooperating with the upright face of the bracket to provide channel runways for the work, said angle bar being pivoted at its upper end upon the bracket and having its lower end adjacent the work supporting member and slideable on the upright face of the bracket relative to the recess in said member.

10. In a machine of the class described, a bracket having a substantially flat upright side and having an opening extending transversely thereof, and means for delivering work to a point in substantially horizontal alignment with the opening including a chute having two runways arranged substantially end to end, one of said runways being fixed to the bracket, and having a portion cooperating with the flat side aforesaid of the bracket to form a channel for the work, and the other of said runways being pivotally connected to the bracket and having a portion cooperating with the flat side aforesaid of the bracket to form a channel for the work.

11. In a machine of the class described, a bracket attachable to a frame of a machine, a chute carried by the bracket including two runways, one being fixed to the bracket, and the other being adjustable relative to the fixed runway and disposed at an angle thereto, and means for directing work from the fixed runway into the movable runway including an adjustable shield over the adjustable runway and having a part overlapping the fixed runway.

12. In a machine of the class described, a frame, a bracket member secured to the frame and having an upright face, a substantially horizontal work supporting member secured to the bracket, means for delivering work to the work supporting member including a chute having two runways arranged substantially end to end and carried by the bracket, each runway cooperating with the upright face of the bracket to provide upper and lower channels for the work, and means for maintaining the work in the lower channel including a shield substantially parallel to the lower channel and having an extension overlapping the lower end of the upper channel.

13. In a machine of the class described, a frame, a bracket member secured to the frame, a substantially horizontal work supporting member carried by the bracket, means for delivering work to the work supporting member including a chute having two inclined runways arranged substantially end to end and carried by the bracket, and means for maintaining the work in the lower runway including a shield adjustably mounted on the upright face of the bracket member in substantially parallel relation to the lower runway and having an extension overlapping the lower end of the upper runway.

14. In a machine of the class described, a bracket having a substantially flat upright face, a substantially horizontal member carried by the bracket adjacent said face for receiving work, and means carried by the bracket for delivering work to said work receiving member, including a chute of substantially L cross section having the base of the L disposed at substantially right angles to the flat face aforesaid of the bracket and having the upright portion of the L substantially parallel to the flat face of the bracket whereby the base and upright portions of the chute cooperate with the flat face of the bracket to form an upwardly opening channel for the work.

15. In a machine of the class described, an upright bracket, a work receiver suspended from said bracket and having a substantially horizontal portion provided with an upwardly opening channel for receiving and supporting the work, and means carried by said bracket for delivering work into the channel, said means including a runway pivotally mounted at its upper end on the bracket and adjustably connected at its lower end to the bracket so that it may be moved in an arc about its pivot to direct work of various size to the upwardly opening channel.

16. In a machine of the class described, the combination with a supporting frame having laterally spaced rails, of a vertically disposed plate-like bracket having laterally projecting attaching portions engaging said rails, means engaging said attaching portions for securing the bracket to the rails, work receiving means below said laterally projecting attaching portions, and means for directing work from points about said attaching portions toward said work receiving means, including means carried by said attaching portions.

17. In a machine of the class described, a bracket adapted to extend transversely of a machine frame and having attaching portions at opposite ends thereof for attachment to a suitable support, work receiving means below said attaching portions, and means for delivering work from a point above said attaching portions to said work receiving means, including a chute having an inclined runway rigid with said bracket, and a cooperating runway pivotally mounted at its upper end on the bracket adjacent the lower end of the inclined runway and adjustably connected to the bracket at its lower end for movement relative to said work receiving means.

18. In a machine of the class described, a bracket attachable to a frame of a machine, a chute carried by the bracket including two runways, one being fixed to the bracket, and the other being adjustable relative to the fixed runway and disposed at an angle thereto, and means for directing work from the fixed runway into the movable runway including an adjustable shield over one of said runways and having a part overlapping the other runway.

GEORGE F. YAGER.
